UNITED STATES PATENT OFFICE.

DONALD F. DUNCAN, OF CHICAGO, ILLINOIS.

DESIGN FOR A CANDY CHEST.

Application filed March 26, 1925. Serial No. 12,883. Term of patent 7 years.

To all whom it may concern:

Be it known that I, DONALD F. DUNCAN, a citizen of the United States, residing at Chicago, in the county of Cook and State of Illinois, have invented a new, original, and ornamental Design for Candy Chests, as shown in the accompanying drawing and described in the following specification.

The single figure of the drawing is a perspective view of the design.

I claim:

The ornamental design for a candy chest substantially as shown.

DONALD F. DUNCAN.
